[57] CLAIM

The ornamental design for a blade attachment for a pneumatic tool or the like, substantially as shown and described.

DESCRIPTION

FIG. 1 is a front perspective view of the blade attachment for a pneumatic tool or the like showing my new design;

FIG. 2 is a top elevation of the blade attachment for a pneumatic tool or the like;

FIG. 3 is a bottom elevation of the blade attachment for a pneumatic tool or the like;

FIG. 4 is a front elevation thereof;

FIG. 5 is a rear elevation thereof;

FIG. 6 is a right side elevation of the blade attachment for a pneumatic tool or the like; and

FIG. 7 is a left side elevation of the blade attachment for a pneumatic tool or the like illustrated in FIGS. 1-6.
